“Stanley Beverage Container,” 1 page, Stanley product publicly disclosed prior to Mar. 6, 2017.

Primary Examiner — Marianne Pandozzi*Assistant Examiner* — Jae Liang(74) Attorney, Agent, or Firm — George C. Rondeau, Jr.;
Davis Wright Tremaine LLP(57) CLAIM

The ornamental design for a handle for a beverage container, as shown and described.

DESCRIPTION

FIG. 1 is a top perspective view of a handle for a beverage container showing our new design;

FIG. 2 is a bottom perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The broken lines in the drawings depict portions of a handle for a beverage container and environmental subject matter that form no part of the claimed design.

1 Claim, 7 Drawing Sheets(56)
